UNITED STATES PATENT OFFICE.

ALICE MOSES, OF BENNINGTON, VERMONT.

BUTTON-FASTENER.

1,340,073.

Specification of Letters Patent.

Patented May 11, 1920.

Application filed October 10, 1919. Serial No. 329,673.

To all whom it may concern:

Be it known that I, ALICE MOSES, a citizen of the United States, residing at Bennington, in the county of Bennington, State 5 of Vermont, have invented a new and useful Button-Fastener; and I do hereby declare the following to be a full, clear, and exact description of the invention, such as will enable others skilled in the art to which 10 it appertains to make and use the same.

The invention relates to button fasteners and has for its object to provide means whereby buttons may be quickly and easily fastened to an article of clothing or re- 15 moved therefrom. At the present time where buttons are sewed on clothing, the buttons become broken when laundered thereby dropping off the clothing.

A further object is to provide a securing 20 means for a button comprising a bowed pin formed from a single piece of spring wire, said spring wire being bent upon itself so as to form a pin section provided with a series of convolutions adapted to be forced 25 through the cloth and then through the eye of a button and finally again passing through the cloth and having its free end held by the body portion of the pin, said convolution preventing this displacement of 30 the button after the pin portion has been forced through the eye thereof.

With the above and other objects in view the invention resides in the combination and arrangement of parts as hereinafter set 35 forth, shown in the drawings, described and claimed, it being understood that changes in the precise embodiment of the invention may be made within the scope of what is claimed without departing from the 40 spirit of the invention.

In the drawings:—

Figure 1 is a perspective view of the button fastener showing the same applied to a button.

Fig. 2 is a longitudinal sectional view 45 through the button showing the same applied to a piece of cloth.

Fig. 3 is a vertical sectional view taken on line 3—3 of Fig. 2.

Referring to the drawing, the numeral 1 50 designates a conventional form of button having a transverse aperture 2 through a lug 3 on the rear face thereof. It is customary to sew the button 1 to the cloth by

passing a series of threads through the aperture 2 and the cloth, however to avoid the use of thread and at the same time provide means for securing the button on the goods so that it can be easily and quickly applied or removed, a pin 4 is provided. The pin 55 4 is made of spring wire and comprises a body portion 5 having at one end thereof a right angled portion 6, the end of which is bent as at 7 to form a loop for the reception of the free end of the pin section 8. The pin section 8 is provided with a compound 60 curve 9, the convolutions of which are adapted to be forced through the aperture 2 in the button so that the corners 10 of the aperture will engage within the convolution 70 11 and be held therein so that the button will be prevented from longitudinal movement on the pin section 8. The rear end of the pin section 8 extends upwardly as at 12 and is bent upon itself as at 13 and merges 75 into the body portion 5 as at 14. The second bend 13 forms a downwardly extending projection 15, which prevents the upward slipping of the cloth upon the portion 12 of the pin section, thereby keeping the cloth 80 in engagement with the rear face of the button. The outer convolution 9 also maintains the cloth in a close position to the lug 3 on the opposite side to the lug 15. The pin section 8 being made of spring material 85 it will be seen that as it is forced through the hole 12 the button 1 will be held against longitudinal movement on the pin section 8, this holding being accomplished by the frictional engagement of the convolutions 90 11 within the aperture 2.

From the above it will be seen that a button fastener is provided which may be easily and quickly applied and one wherein buttons may be easily and quickly removed 95 from clothing before laundering and quickly replaced after laundering.

The invention having been set forth what is claimed as new and useful is:—

A button securing pin comprising a body 100 member, said body member being bent at an acute angle at one of its ends, said acute angle portion being bent upon itself so as to form a downwardly extending projection, the free end again being bent upon itself so as to 105 form a pin portion, said pin portion being provided with a series of convolutions adapted to be forced through a cloth thence

through a transverse aperture in the button, thence through the cloth at the opposite side of the button until the rear convolution engages within the aperture of the button and 5 a hook carried at the end of the body member for the reception of the free end of the pin section.

In testimony whereof I have signed my name to this specification in the presence of two subscribing witnesses.

ALICE MOSES.
